CLAIM

The ornamental design for a dispensing container for air freshener, as shown and described.

DESCRIPTION

FIG. 1 is a front elevational view of a dispensing container for air freshener showing my new design;

FIG. 2 is a right side elevational view thereof, the left side being a mirror image of the right side shown;

FIG. 3 is a rear elevational view thereof;

FIG. 4 is a bottom plan view thereof; and,

FIG. 5 is a top plan view thereof.
